[57] CLAIM

The ornamental design for a watch housing, as shown and described.

DESCRIPTION

FIG. 1 is a top view of a watch housing in accordance with our invention;
 FIG. 2 is a left side elevation view of the watch housing of FIG. 1;
 FIG. 3 is a right side elevation view of the watch housing of FIG. 1;
 FIG. 4 is a bottom view of the watch housing of FIG. 1;
 FIG. 5 is a front view of the watch housing of FIG. 1; and,
 FIG. 6 is a back view of the watch housing of FIG. 1.
 The broken line showings of a dial in FIGS. 1-3 and 5-6 are environmental only and form no part of the claimed design.
